UNITED STATES PATENT OFFICE.

RUSSELL D. GEORGE, OF BOULDER, COLORADO.

FUEL-SAVING DEVICE.

Application filed June 16, 1923. Serial No. 645,904.

To all whom it may concern:

Be it known that I, RUSSELL D. GEORGE, a citizen of the United States, residing at Boulder, county of Boulder, and State of Colorado, have invented certain new and useful Improvements in Fuel-Saving Devices; and I do declare the following to be a full, clear, and exact description of the invention, such as will enable others skilled in the art 10 to which it appertains to make and use the same, reference being had to the accompanying drawings, and to the characters of reference marked thereon, which form a part of this specification.

15 This invention relates to fuel saving devices of the type sometimes referred to as "smoke abaters" and has special reference to an improved form of this type of device.

In the burning of coal two distinct chemical processes are involved. The first is the destructive distillation of the coal which takes place at a comparatively low temperature, and does not require the aid of air or oxygen. The second is the oxidation or combustion of materials produced by destructive distillation, and takes place at comparatively high temperatures by the aid of oxygen from the air.

The destructive distillation products 20 which are chiefly concerned in the combustion are hydrogen, carbon monoxide, hydrocarbons, and coke or carbon, and they may be called the prepared fuel. It is the oxidation or combustion of these products which 25 produces the heat, and the maximum yield of heat is obtained only by complete combustion.

Perfect combustion can be secured only by 30 supplying the proper amount of oxygen at the proper time, bringing it into intimate contact with the prepared fuel, and securing the necessary heat for full and quick ignition. Such conditions are rarely obtained in practice, and the principal obstacle in the 35 way of securing them lies in the intermittent feeding of the furnace. When the feed door is opened a flood of cool air is drawn into the fire box by the draft, replacing the hot vapors over the fire bed, greatly reducing the temperature, and weakening the draft by substituting heavier cool air for the highly heated and lighter vapors rising from the fire bed. The fresh coal added is

cold, is a poor conductor of heat, and further reduces the temperature of the fire bed, and of the vapors over the fire bed. The coal added tends to impede the draft from below the grate, and reduces the supply of oxygen in contact with the prepared fuel. As a consequence of these conditions combustion is extremely slow and may almost cease.

But the temperature of the fire bed is still ample for the distillation process which is hastened by the fresh coal added. Thus the material for combustion is supplied most rapidly at a time when the conditions for combustion are poorest. As a consequence large quantities of finely divided carbon (colloidal), and large volumes of combustible gases—hydrogen, carbon monoxide and hydrocarbons—pass out of the chimney unburnt. The results of these conditions are:

1. An excessive production of the prepared fuel—hydrogen, carbon monoxide, hydrocarbons, and coke or carbon in finely divided form—accumulating over the fire bed and shutting out the air.

2. An insufficient supply of air for the combustion of the prepared fuel, and a lack 80 of contact between the oxygen of the air and the fuel.

3. A greatly reduced temperature, frequently below the ignition point of the fuel.

4. Volumes of unburnt fuel gases and dense 85 smoke are drawn up the chimney and wasted. The waste in gases is proportional to the smoke density.

To secure complete combustion there must be an adequate supply of air immediately 90 over the fire bed, intimately mingled with the fuel gases and finely divided carbon rising from it, and the temperature must be high enough for prompt and rapid ignition.

The process and apparatus herein described supply the needed air, mingle it intimately with the gases and carbon rising from the fire bed, raise the temperature of the mixture to the point of ready ignition and secure complete combustion, and 100 the consequent saving of fuel.

The process consists in conducting heated air down upon the surface of the fire bed, mingling it intimately with the prepared fuel, and raising the temperature of the mixture above the ignition point.

The apparatus consists of an air duct or passage of plate or cast-iron terminating in a grid nozzle, and provided with an automatically operating damper or shutoff within 5 in the duct. It is attached to the inside of the feed door of the furnace and extends well into the fire chamber over the fire bed so as to place the heated air where it is needed to accomplish the purpose. The inner 10 end of the apparatus is built heavy so as to secure the storage of a large amount of heat during the periods between the feedings of the furnace. The grid or latticed nozzle is designed:

- 15 1. To baffle the passing air, delaying it long enough to raise its temperature.
2. To present a large surface of radiation from which heat passes into the air traveling through it to the fire bed.
- 20 3. To break and scatter the air current causing it to mingle with the gases rising from the fire bed.
4. To cause a wide lateral distribution of the air over the fire bed and to give it a 25 downward course to carry it to the desired place against the upward movement of the draft toward the chimney, and thus secure a mingling of the air with the fuel gases and carbon over the fire bed.
- 30 5. The drawings show a preferred form of the apparatus, but modifications are designed to meet the conditions arising from different furnace designs and different coals used.
- 35 6. Thus, for furnaces having a heavy insulation or lining there is provided a hinged extension of the duct which will carry the air farther into the furnace. This is also desirable in the case of furnaces having a 40 long fire bed.

When the feed door is closed the damper or shut-off in the duct is automatically opened and air immediately pours into the fire box. A timing valve is arranged to close 45 the damper in the time which by experience is found to be sufficient to prevent the fuel loss consequent upon the conditions arising from the operation of feeding the furnace, or, in other words, in the time which experience proves to be necessary to re-establish 50 normal combustion conditions in the fire box, and to render the use of the apparatus no longer necessary until the next feeding. The closing of the butterfly damper is done in such a way as to aid in giving the passing air a downward movement along the lower side of the duct.

In the longer, hinged apparatus, the hinge is placed just back of the nozzle so that 60 when the door is opened the nozzle swings over toward the hinge line of the door, and so reduces its length that it will pass out of the doorway.

In order to more clearly describe my invention, I shall have reference to the ac-

companying drawings in which the present preferred embodiment is shown in detail, and in which:

Fig. 1 shows a front elevation of a furnace door to which my improved fuel saving device has been applied;

Fig. 2 is a section taken on line 2—2, Fig. 3;

Fig. 3 is a section taken on line 3—3, Fig. 2;

Fig. 4 is a view looking in the direction of the arrow 4 in Fig. 5;

Fig. 5 is a side elevation of the parts shown in Fig. 4 looking in the direction of the arrow 5;

Fig. 6 is a section taken on line 6—6, Fig. 3;

Fig. 7 shows a modification intended to be used in connection with furnaces having a very thick insulating lining or a very deep 80 or long fire bed; and

Fig. 8 shows how the parts shown in Fig. 7 are adapted to bend so as to permit the door to be opened and closed.

The same reference numerals will be employed to designate the same parts throughout the several views. In the drawings numeral 1 represents a fuel door of a furnace and 2 the stationary frame to which it is connected by means of hinges 3 in the usual manner. The furnace wall 4 may be of brick as it usually is when the furnace relates to a steam boiler and in such case is of considerable thickness. My device is, however, equally well adapted to be used on any ordinary hot air or hot water heater, such as are ordinarily employed in connection with the heating of residences and in such cases the wall 4 is comparatively thin. The door 1 is formed with a central opening and has secured to the inside thereof an air duct 5 preferably formed of cast-iron. This air duct has a substantially rectangular tubular inlet canal 6 whose inner 95 dimensions are substantially the same as that of the opening in the door. Lugs 7 are formed near the outer end of the tubular inlet canal and are provided with holes for the reception of bolts 8, by means of which the air duct is secured to the inner surface of the door in the manner shown in Figs. 2 and 3. The inner end of the air duct is enlarged by having the sides 9 outwardly inclined and the bottom 10 downwardly inclined in the manner shown in Figs. 2 and 3.

This enlarged end, which I shall refer to as the nozzle, is provided with a plurality of openings 11, the axes of which are angularly inclined with each other in such a way that the air emerges in a plurality of downwardly and outwardly directed streams which mingle with the gases arising from the fire bed. The inner end or nozzle is purposely made massive so that it will store a large quantity of heat during the periods between 100 105 110 115 120 125 130

the firing in order that the air which enters the furnace through the openings 11 may become highly heated. The total cross-sectional area of the openings 11 is less than 5 the cross-sectional area of the inlet canal so that the air is retarded in its flow, whereby more thorough heating is secured. The expansion of the air, due to heating, also acts as a baffle, as the volume is thereby increased.

10 Directly in front of the entrance to the openings 11 and within the canal 6 I place a plurality of louvers 12 which are pivotally connected at 13 to the vertical sides of the air canal (Fig. 2). A rod 14 is pivotally secured 15 to each louver at 15 and is provided at each end with nuts 16 by means of which it can be held in adjusted position. The function of the louvers 12 is to regulate the maximum quantity of air that will be permitted 20 to enter the openings 11 at a given pressure. The conditions under which a furnace operates with respect to the draft and the quality of coal burned is different for every installation and a device that 25 would be adjusted to conform to the requirements of one case would not be suitable for use in another place. The adjustment afforded by the louvers 12 enables the device to be readily adapted to any ordinary 30 installation. Attention is called to the fact that the louvers 12 are so arranged that when in their partly closed position the space between them is downwardly and inwardly inclined so that the air will be given 35 a downward direction. Within the air canal 6 between the louvers and the furnace door, I place a damper 17 which is pivotally mounted on the rod 18. The damper is slightly wider than the air duct so that when 40 the damper is closed, it occupies a position like that shown in Fig. 2 forming an angle of about sixty degrees with the lower surface of the channel, and, while it is in any partly open position, the air will be given 45 a downward direction which causes the bulk of the air to travel along the lower side of the air canal and to enter the lowermost of the openings 11 which are heated to a higher temperature than the others and 50 which also distribute the air to better advantage over the fire.

Attention is directed at this point to the fact that the damper and the louvers, as well as the adjusting and operating mechanism, are all enclosed within the air canal 55 so as to be protected from injury.

The damper 17 is provided on one side with an arm 19 to which the connecting rod 20 is pivotally attached. The other arm of 60 rod 20 is pivotally secured by means of a bolt 21 to the end of the crank arm 22 of the dash pot 23 which may be a standard dash pot of the type employed in connection with doors. Since the dash pot 23 is merely a 65 standard and well known article, it has not

been shown in detail and will not be described, except to this extent: That it is so constructed that it permits the damper 17 to move freely from closed to open position and retards the closing of the damper to 70 any extent desired, being provided with means for adjusting the rate of closing. It is also provided with a spring that tends to move the damper to closed position in opposition to the action of the dash pot. 75 Pivotedly secured to one of the vertical sides of the air canal 6, by means of a pin 24, is a lever 25 which projects downwardly below the bottom of the air canal 6 in the manner shown in Fig. 2. Secured to the 80 outer surface of the damper is a lug 26 which is in position to be engaged by the upper end of the lever 25 when the latter is moved about its pivot 24 in a counter-clockwise direction. When a force is applied to 85 the lever 25, which moves it in a counter-clockwise direction about its pivot, the upper end thereof will strike the lug 26 and move the damper to open position (shown in dotted lines in Fig. 2), from which position the damper is slowly returned to closed position by means of the spring and dash pot above referred to. If a force is applied to the 90 lever 25, which rotates it in a clockwise direction, it swings freely. The above described characteristics of the lever 25 and its mounting is taken advantage of in obtaining automatic opening of the damper as the door is closed after each feeding of fuel. A lug 95 or projection 27 is secured to the lower side 100 of the door frame. This lug projects upwardly into the path of the lower end of the lever 25 so that when the door is opened, the projection causes the lever to rotate in a clockwise direction about its pivot, which, 105 as above explained, is without effect. When the door is closed, the projection 27 will cause the lever to rotate in a counter-clockwise direction which moves the damper to 110 open position (shown dotted in Fig. 2).

In the manner and by the means above described, I obtain the opening of the damper as the door closes. This is an important feature for the reason that by setting the mechanism, by the closing action of the door, the damper will always remain open a predetermined time after the door closes. If, for example, the damper were opened when the door was opened, the time which the damper remained open after the door 115 was closed would be indeterminate as it would depend upon the time that the door remained open. I therefore consider this an important feature of my invention. In order to fully protect the dash pot 23 and 120 to give a finished appearance to the furnace door, I secure to the front side thereof an enclosing casing, which is held in place on the door by means of screws 29. The ends 125 and front of said casing is provided with 130

stationary louvers 30 which are spaced apart a sufficient distance to permit the maximum amount of air to enter. The casing 28 completely encloses the movable and vulnerable parts and prevents them from becoming accidentally broken or purposely tampered with by unauthorized parties.

In the drawings the air duct 5 is shown as formed from an integral casting, which 10 is perfectly feasible and possesses several advantages over an assembled air duct, but I desire to have it understood that my invention is not to be limited to the specific method employed in the construction of the 15 device, and that the air duct can be made from a plurality of separate castings or of plates assembled to form a structure like that shown and described without thereby departing from the invention.

20 The mechanism shown and described in Figs. 1 to 6 is intended for a furnace having a wall of average thickness. Where my device is to be used in connection with furnaces having extra thick walls or where the 25 fire bed is long, it is necessary to make the air duct longer, and it often happens that it must be made of such length that if it were made rigid as shown in Figs. 1 to 6, the door could not be opened. For the purpose of being able to employ air ducts of the proper 30 length and also be able to open and close the door, I have devised a hinged air duct which is shown in Figs. 7 and 8, and which consists of a rectangular, tubular inlet canal 6^a, similar to the part 6 in Figs. 2 and 3. This part contains the damper 17 and damper operating mechanism. The inner end of the tubular inlet canal is notched and has inwardly 35 extending sides 31. Pivotally secured to the inner end of member 6^a is the nozzle 32, which has a portion thereof 33 outwardly curved on an arc whose center is the pivot 34. The nozzle 32 is constructed and shaped exactly the same as the corresponding part 40 shown in Figs. 2 to 5, except as to the end, which cooperates with the inner end of the part 6^a. This end has the aforesaid arcuate portion 33 on one side and the other side is cut away in the manner shown in Figs. 7 45 and 8. This construction permits the part 32 to turn about its pivot 34 in the manner shown in Fig. 8 sufficiently to permit the door to be opened and closed. Formed integral with the nozzle 32 are pairs of ears 35 between which is pivoted the rollers 36 which are adapted to cooperate with the sides 37 of the opening or with specially constructed guides that assist in moving the parts into the position shown in Fig. 8 and back again 50 into the position shown in Fig. 7 by means such as that just described. A very long air duct can be employed with an ordinary sized door opening.

60 From the above description, it will be apparent that I have produced a fuel saving

device for furnaces that has many points of merit, among which I will call attention to the following:

The damper and damper mechanism is entirely enclosed and protected from injury. 70

The cross-section of the openings in the nozzle is less than the cross-section of the inlet canal and therefore the air flow is retarded so that it will absorb more heat from the heated surfaces with which it comes in 75 contact.

The nozzle is designed so that it will spread the air laterally and direct it downwardly onto the coal bed.

80 The nozzle is made massive so as to store a large quantity of heat and is provided with a large number of comparatively small openings so that the air comes into contact with a large amount of radiating surface. In the smaller devices the friction or radiating surface with which the air contacts is over 12 85 square feet.

89 The air is not merely introduced into the combustion chamber, but it is directed to the point where it can be most efficiently used to meet the chemical and physical conditions required for complete combustion.

95 The damper is so positioned that it directs the bulk of the air along the lower side of the duct or canal where it will come in contact with the hottest surfaces and will enter the lowermost openings in the nozzle. The damper is automatically opened when the door closes, thereby assuring that the same 100 will close a predetermined time after the door is closed. The time that the damper remains open is determined by the adjustment of the dashpot which can be varied at will.

105 The maximum amount of air that can enter may be controlled by the adjustable louvers to suit the needs of the furnace, the character of the coal and the intensity of the firing.

110 The entire apparatus, except the enclosing casing, is inside and therefore there is nothing to interfere with or add to the duties of the fireman.

115 The device is very simple and consists of only a very few parts which are substantial and of great strength so that there is a minimum of breakage.

Having now described my invention, what I claim as new is:

120 1. In combination, a furnace, a wall enclosing and forming a combustion chamber, said wall having a feed opening therein, a door hingedly connected to one side of said opening, said door having an opening therein, an air duct secured to the inner surface of said door, the inner end of said duct being formed with a plurality of openings, a damper within said duct adapted to close the same, means for normally maintaining the damper in closed position, means for opening the damper whenever 125 130

the door is closed, means for retarding the closing of said damper, a plurality of louvers between the damper and the ends of said openings, and means for adjusting the size of the openings between said louvers.

2. In combination, a furnace, a wall enclosing and forming a combustion chamber, said wall having a feed opening there-in, a door hingedly connected to one side of said opening, said door having an opening therein, an air duct secured to the inner surface of said door, the inner end of said duct being formed with a plurality of openings, a damper within said duct adapted to close the same, means for normally maintaining the damper in closed position, means for opening the damper whenever the door is closed, means for retarding the closing of said damper, a plurality of louvers between the damper and the ends of said openings, and means for adjusting the size of the openings between said louvers, said damper and said louvers being inclined downwardly and inwardly when in partly open position.

3. In a furnace in combination, a wall enclosing and forming a combustion chamber adapted for the burning of carbonaceous fuel, said wall having a feed opening therein, a door adapted to close said opening, said door being movably secured in place so as to be readily opened, said door having an opening therein, an air duct secured to the inner surface of said door, the inner end of said air duct being provided with a plurality of divergent openings whose combined cross-sectional area is less than the cross-sectional area of said air duct, a damper within said duct, said damper being adapted to close the passage-way through the duct, means for normally maintaining the damper in closed position, means for opening said damper whenever the door is closed, means comprising a dash pot for retarding the closing of the damper, means for adjusting the rate at which the damper closes, and means between the damper and the openings for controlling the maximum amount of air that may enter said openings under predetermined conditions, said last named means being provided with an adjusting mechanism.

4. An air duct adapted to be secured to the inner surface of a furnace door, said duct having its inner end closed by a thick wall which is perforated by a plurality of openings whose greatest transverse dimension is less than the thickness of the wall, a damper within said duct, said damper being movably mounted therein and adapted to close the opening through said duct, and a plurality of spaced, adjustable louvers between the damper and the openings.

5. An air duct adapted to be secured to the inner surface of a furnace door, said duct having its inner end closed by a thick wall which is perforated by a plurality of openings whose greatest transverse dimension 70 is less than the thickness of the wall, a damper within said duct, said damper being movably mounted therein and adapted to close the opening through said duct, and a plurality of spaced, adjustable louvers 75 between the damper and the openings, said louvers having means for adjusting the area of the opening between them.

6. In combination, a wall provided with an opening, a door hingedly connected to the wall and adapted to close said opening, said door having an opening therein, an air duct secured to the inner surface of the door, a damper within said duct, said damper being pivotally mounted on a horizontal axis, 80 a lever pivotally mounted to one side of said duct, a portion of said lever being within the duct and another portion being without the duct, the part of the lever within the duct being adapted to engage 85 the damper and rotate it on its axis when the lever is moved in one direction.

7. In combination, a wall provided with an opening, a door hingedly connected to the wall and adapted to close said opening, 90 said door having an opening therein, an air duct secured to the inner surface of the door, a damper within said duct, said damper being pivotally mounted on a horizontal axis, a lever pivotally mounted to 95 one side of said duct, a portion of said lever being within the duct and another portion being without the duct, the part of the lever within the duct being adapted to engage the damper and rotate it on its axis 100 when the lever is moved in one direction, and means secured to the opening in the wall and adapted to project into the path of the outer end of the lever and to swing the lever about its pivot as the door is 105 opened and closed.

8. In combination, a wall provided with an opening, a door hingedly connected to the wall and adapted to close said opening, 110 said door having an opening therein, an air duct secured to the inner surface of the door, a damper within said duct, said damper being pivotally mounted on a horizontal axis, a lever pivotally mounted to one side of said duct, a portion of said lever being within the duct and another portion being without the duct, the part of the lever within the duct being adapted to engage 115 the damper and rotate it on its axis when the lever is moved in one direction, means secured to the opening in the wall and adapted to project into the path of the outer end of the lever and to swing the lever about its pivot as the door is 120 opened and closed, said parts being so re- 125 130

lated that the lever opens the damper when the door is closed.

9. In combination, a wall provided with an opening, a door hingedly connected to the wall and adapted to close said opening, said door having an opening therein, an air duct secured to the inner surface of the door, a damper within said duct, said damper being pivotally mounted on a horizontal axis, a lever pivotally mounted to one side of said duct, a portion of said lever being within the duct and another portion being without the duct, the part of the lever within the duct being adapted to engage the damper and rotate it on its axis when the lever is moved in one direction, means secured to the opening in the wall and adapted to project into the path of the outer end of the lever and to swing the lever about its pivot as the door is opened and closed, said parts being so related that the lever opens the damper when the door is closed and means for yieldingly holding the damper in closed position.

10. In combination, a wall provided with

an opening, a door hingedly connected to the wall and adapted to close said opening, said door having an opening therein, an air duct secured to the inner surface of the door, a damper within said duct, said damper being pivotally mounted on a horizontal axis, a lever pivotally mounted to one side of said duct, a portion of said lever being within the duct and another portion being without the duct, the part of the lever within the duct being adapted to engage the damper and rotate it on its axis when the lever is moved in one direction, means secured to the opening in the wall and adapted to project into the path of the outer end of the lever and to swing the lever about its pivot as the door is opened and closed, said parts being so related that the lever opens the damper when the door is closed, means for yieldingly holding the damper in closed position, and means for causing the damper to close slowly.

In testimony whereof I affix my signature.

RUSSELL D. GEORGE
